EXHAUST SILENCER

Earl G. Gunn, Jackson, Mich., assignor to
Walker Manufacturing Company, Racine, Wis.,
a corporation of Wisconsin

Application July 30, 1937, Serial No. 156,561

8 Claims. (Cl. 181—54)

The present invention relates generally to exhaust silencers for internal combustion engines of motor vehicles. More particularly it relates to an improved form of exhaust silencer which embodies a retroverted substantially continuous exhaust passage and which includes as an integral portion of the construction, a resonating chamber constructed and arranged to eliminate certain objectionable sounds resulting from normal operation of the motor with a conventional muffler.

The exhaust silencer of the present invention is of what is conventionally known as, the three tube type as contrasted to a straight tube muffler. Silencers of this generic type usually include three longitudinally disposed tubes, one of which connects with the exhaust manifold, another connects with the tail pipe, and a third serves to provide an interconnection between the first two. Communication between the inlet tube and the outlet tube through the return tube is accomplished by means of cross-overs which cross-overs comprise fittings which serve to change the direction of flow of the gas through an angular distance of 180°.

The present invention contemplates the provision of a resonator chamber interiorly of the casing which surrounds these tubes and includes an opening or pipe establishing communication between one of the cross-overs and this resonator chamber.

It is well recognized that resonating chambers of this generic type have a silencing effect which depends upon three co-related factors, namely, the volume of the chamber, the size of the opening, and the length of the tube which establishes communication with the chamber. While it will be readily understood that different types of motors running at different speeds in various set-ups produce certain objectionable sounds during the normal ranges of operation, it will be appreciated that the particular resonator chamber may be so proportioned, constructed, and arranged that this resonator chamber may serve to eliminate the undesirable sound emanating from a particular construction and arrangement.

Still further, the present invention contemplates the provision of an enclosed chamber in the opposite end of the muffler construction from the resonator chamber, through which last mentioned chamber the outlet pipe of the muffler passes. The present invention contemplates the provision of tangential openings provided in the outlet pipe throughout the zone of the pipe which passes through this last mentioned chamber in

order that this chamber may also act as a resonator for eliminating certain undesirable sounds.

Many other and further objects, advantages, and features of the present invention will become clearly apparent from the following specification when considered in connection with the accompanying drawings forming a part thereof.

In the drawings:

Figure 1 is a longitudinal sectional view through a muffler construction embodying the improvements of the present invention.

Fig. 2 is a transverse sectional view taken substantially on the line 2—2 of Fig. 1 illustrating in detail the construction and arrangement of the tubes interiorly of the muffler, the cross-over duct and the tube communicating with the resonator chamber.

Fig. 3 is an enlarged fragmentary transverse sectional view through one of the louvered tubes illustrating the manner in which the vents are provided therein.

Fig. 4 is a longitudinal sectional view through a somewhat modified form of silencer construction embodying the improvements of the present invention.

Fig. 5 is a transverse sectional view taken substantially on the line 5—5 of Fig. 4 illustrating in detail cross-sectional configuration of the silencer disclosed therein.

It will be readily apparent to those skilled in the art that the silencer construction disclosed in the drawings of the present application may be constructed in many and various different ways and forms and yet at the same time embody therein the improvements of the present invention. It has been found preferable, however, to fabricate the silencer construction in the manner shown in the drawings and as hereinafter described in detail.

As is conventional in constructions of this general character, the silencer as a whole includes a generally cylindrical sheet metal casing 5 which is closed and sealed at its ends by means of partitioning members or end walls 6 and 7, respectively. Interiorly, the casing is provided with a pair of spaced baffles 8 and 9 which serve the function of dividing the interior of the casing into compartments of predetermined size and also serve the purpose of supporting the tubes of the silencer in the manner described in detail below.

It will of course be apparent that in constructing an exhaust silencer of the type shown in the drawings the volume of the various chambers formed interiorly of the casing may be conveniently regulated by adjusting the baffles in pre-

determined longitudinal position. The importance of this feature of the invention will become more clearly apparent as the description proceeds.

5 The tubes defining the passageway for the exhaust gases include an inlet tube 10 which passes through the end wall 6 of the casing in sealed relation with respect thereto and which is adapted, as is conventional in constructions of this general character, to be connected by a suitable 10 pipe to the exhaust manifold of the motor with which the silencer is adapted to be used.

As is clear by reference to Fig. 1 of the drawings, this inlet tube 10 is not only supported in sealed relation to the end wall member 6 but is 15 also supported in sealed relation with respect to the partition members 8 and 9.

20 The outlet or discharge tube 11 is mounted in sealed relation to and passes through the end wall partition member 7 and is likewise supported in the baffles or partitioning members 9 and 8 in substantially the same manner as the inlet tube 10. Also mounted in the baffle members 8 and 9 is 25 the third or intermediate tube 12 seen in dotted lines in Fig. 2.

25 From the foregoing, it will be appreciated that the baffle members 8 and 9 serve to divide the casing structure generally into three compartments 13, 14 and 15, respectively, the size of which may be conveniently regulated by the particular 30 position of the baffle members 8 and 9. The rear end of the inlet tube 10 terminates approximately at the baffle member 9 and likewise the rear end of the intermediate tube 12 terminates at this baffle. Communication between the respective 35 rear ends of these tubes is established by means of a cross-over 17 which may be in the form of a semi-circular coupling member which is preferably flanged and welded to the baffle 9 in order to provide a conduit of substantially uniform cross 40 sectional area establishing communication between the rear end of the tube 10 and the rear end of the tube 12. A substantially similar cross-over member 18 similarly serves to establish communication between the forward end of the outlet 45 pipe 11 and the rear end of the intermediate tube 12.

It will be readily seen that the cross-over 17 is located wholly within the chamber 13 but no communication is afforded between the interior 50 of the cross-over 17 and the interior of the chamber 13. However, the cross-over 18 is located wholly within the interior of the chamber 15 and, in substantially its mid-portion, it is provided with a projecting substantially cylindrical tube 19 55 which establishes communication between the interior of this cross-over member 18 and the interior of the chamber 15. The chamber 15 thus constitutes a resonator chamber which will serve to silence sounds of certain frequencies. The 60 function of this resonator in the elimination of sounds from the motor depends, as mentioned above, upon its volume, the diameter of the pipe 19 and the length of the pipe 19. It will be readily appreciated that these factors may be controlled in order to obtain maximum effectiveness in a 65 particular installation.

70 The portions of the tubes 10, 11 and 12 which are located within the chamber 14 preferably are provided with tangential louvers 20 which have been found to be particularly effective in the elimination of certain sounds. The portion of the tube 11 which lies within the closed chamber 13 is preferably provided with louvers 21 which construction has likewise been particularly effective 75

in the elimination of sounds of certain frequencies.

7 In the form of the invention illustrated in Figs. 4 and 5, a somewhat modified form of muffler construction is illustrated, but it will be seen 5 that the exhaust silencer construction shown therein embodies the same inventive improvements set forth in connection with the preferred form of the invention illustrated in Figs. 1 to 3, inclusive. In this form the silencer comprises 10 a generally oval sheet metal housing 25 which has intermediate headers 30 and 31 welded in place therein. These headers 30 and 31 are each spaced inwardly from the axial ends of the housing 25 in order to provide for the chambers hereinafter described. The device shown comprises an inlet tube 33 which passes through and is supported in an end wall member 34 serving to close the said end of the casing 25. An outlet tube 35 extends through and is supported in an end wall 20 member 36 which serves to close the rear end of the casing 25. The inlet tube 35 passes through the partition members 30 and 31 and is mounted in sealed relation with respect thereto, and in a similar manner the inlet tube 33 passes through 25 these partitions and is sealed with respect thereto. It will be noted that the inlet tube terminates substantially flush with the partition member 31 and the outlet tube terminates substantially flush with the partition member 30. A return tube 37 30 is mounted in the partition members 30 and 31 and is connected with the inlet tube 33 and outlet tube 35 by means of cross-overs 38 and 39, respectively, which are similar in construction and arrangement to the cross-overs 17 and 18 disclosed in connection with the preferred embodiment of the invention.

It will be appreciated that the partition member 30 together with the casing 25 and end wall member 34 forms an enclosed chamber 40 which 40 communicates with the exhaust passage through a projecting pipe or tube 41 in the cross-over 39, thus providing a sound resonator chamber in communication with the exhaust passage. As was the case in connection with the preferred embodiment of the invention, the inlet tube, outlet tube, and return tube are each provided with a series of louvers 44 which permit the escape of gases into the central chamber of the device. The portion of the inlet tube which extends through 50 the chamber defined by the partition 31 and end wall 36 may similarly be provided with a series of louvers if desired.

From the foregoing it will be readily understood that the exhaust silencer illustrated and 55 described is an extremely simple, cheap and easily fabricated construction which may conveniently be proportioned to operate effectively with many and various types of motors.

Many modifications of the above described construction falling within the scope of the invention as defined in the subjoined claims will be 60 clearly apparent to those skilled in the art.

What is claimed is:

1. In an exhaust silencer construction having a 65 plurality of tubes and having cross-overs interconnecting said tubes to define a retroverted exhaust passage having a substantially uniform cross-sectional area throughout its length, a casing defining a sound resonator chamber surrounding and enclosing one of said cross-overs, and means defining an opening between the interior of said cross-over and said chamber.

2. In an exhaust silencer construction having a 70 plurality of laterally spaced tubes and having 75

cross-overs extending transversely of and interconnecting said tubes to define a continuous retroverted exhaust passage, a casing surrounding said tubes, said casing having a chamber formed 5 therein which encloses one of said cross-overs, said one cross-over having an opening in the wall thereof establishing communication between the interior of said one cross-over and said chamber.

3. In an exhaust silencer construction having a 10 plurality of laterally spaced tubes and having cross-overs extending transversely of and interconnecting said tubes to define a substantially continuous retroverted exhaust passage of substantially uniform cross-sectional area throughout, a casing surrounding said tubes, a sound resonator chamber formed interiorly of said casing and enclosing one of said cross-overs, and a tube associated with said one of said cross-overs, one end of said tube opening directly into said 15 chamber and the other end thereof opening directly into said one cross-over.

4. In an exhaust silencer construction having a plurality of laterally spaced tubes and having cross-overs extending transversely of and interconnecting said tubes whereby to define a retroverted exhaust passage, a casing surrounding said tubes, baffles within said casing serving to support said tubes and serving to divide said casing 20 interiorly into a plurality of closed chambers, one of said cross-overs being positioned in one of said chambers, and means defining an opening in said one of said cross-overs directly communicating the interior of said one of said chambers with the interior of said one cross-over.

35 5. In an exhaust silencer construction having a plurality of laterally spaced tubes and having cross-overs extending transversely of and interconnecting said tubes whereby to define a retroverted exhaust passage, a casing surrounding said tubes, baffles within said casing serving to support said tubes and serving to divide said casing 30 interiorly into a plurality of closed chambers, one of said cross-overs being positioned in one of said chambers, and means defining an opening in said one of said cross-overs directly communicating the interior of said one of said chambers with the interior of said one cross-over, and louvres in said tubes establishing communication between the said exhaust passage and the remainder of the chambers formed in said casing.

40 6. In an exhaust silencer construction having a plurality of laterally spaced tubes and having cross-overs extending transversely of and interconnecting said tubes whereby to define a retroverted exhaust passage, baffles within said 45

casing serving to support said tubes and divide said casing interiorly into a plurality of closed chambers, a branch tube having one end opening directly into one of said chambers and the other end opening directly into one of said cross-overs 5 whereby to provide a sound resonator chamber in communication with said exhaust passage.

7. An exhaust silencer comprising a casing having end walls closing the same at its opposite ends, a pair of baffles interiorly of said casing 10 dividing the same into a front compartment, a central compartment and a rear compartment, an inlet tube passing through one of said end walls and both of said baffles and mounted in sealed relation with respect thereto, an outlet tube 15 passing through the other of said end walls and said baffles and likewise in sealed relation with respect thereto, an intermediate tube extending through said central compartment and baffles and supported in said baffles in sealed relation 20 with respect thereto, a cross-over interconnecting the forward end of said outlet tube and the forward end of said intermediate tube, said cross-over lying within said forward compartment, and means defining direct communication 25 between the interior of said cross-over and the interior of said forward compartment whereby to provide a sound resonator.

8. An exhaust silencer comprising a casing having end walls closing the same at its opposite 30 ends, a pair of baffles interiorly of said casing dividing the same into a front compartment, a central compartment and a rear compartment, an inlet tube passing through one of said end walls and both of said baffles and mounted in sealed 35 relation with respect thereto, an outlet tube passing through the other of said end walls and said baffles and likewise in sealed relation with respect thereto, an intermediate tube extending through said central compartment and baffles 40 and supported in said baffles in sealed relation with respect thereto, a cross-over interconnecting the forward end of said outlet tube and the forward end of said intermediate tube, said cross-over lying within said forward compartment, 45 means defining direct communication between the interior of said cross-over and the interior of said forward compartment whereby to provide a sound resonator, and louvres in the portions of said inlet, outlet and intermediate tubes within 50 said central compartment to establish communication between the interior of said tubes and said central compartment.

EARL G. GUNN.
